CLAIM

The ornamental design for a pacifier simulative of a monkey, as shown and described.

DESCRIPTION

FIG. 1 is a top plan view of a pacifier simulative of a monkey, according to the present design;

FIG. 2 is a right side elevational view thereof;

FIG. 3 is a front side elevational view thereof;

FIG. 4 is a left plan view thereof;

FIG. 5 is a bottom plan view thereof;

FIG. 6 is a rear elevational view thereof;

FIG. 7 is a top, rear, right perspective view thereof; and,

FIG. 8 is a top, front, right front perspective view thereof.

The broken lines shown in the figures depict portions of the pacifier simulative of a monkey that form no part of the claimed design.

1 Claim, 2 Drawing Sheets
